CHARLES D. MILLER, OF WEST MERIDEN, CONNECTICUT, ASSIGNOR TO HIMSELF AND C. H. WARNER, OF SAME PLACE.

Letters Patent No. 65,498, dated June 4, 1867.

IMPROVEMENT IN ATTACHING THILLS TO CARRIAGES.

The Schedule referred to in these Letters Patent and making part of the same.

TO ALL WHOM IT MAY CONCERN:

Be it known that I, CHARLES D. MILLER, of West Meriden, in the county of New Haven, and State of Connecticut, have invented a new Improvement in Carriage Shackles; and I do hereby declare the following, when taken in connection with the accompanying drawings, and the letters of reference marked thereon, to be a full, clear, and exact description of the same, and which said drawings constitute part of this specification, and represent, in—

Figure 1, a side view.

Figure 2, a top view.

Figure 3, a longitudinal central section.

Figure 4, the same, the parts in different position.

Figure 5, the perspective view of the pivot; and, in

Figure 6, a detached view of the part B.

This invention relates to an improvement in the attachment of the pole or shaft to carriages, and consists in the peculiar construction and combination of the parts whereby the use of rivets, bolts, or other detachable parts is entirely avoided.

To enable others skilled in the art to construct and use my improvement, I will proceed to describe the same as illustrated in the accompanying drawings.

A is the clip or strap by which the coupling is attached to the carriage axle; B the strap to which the pole or shafts are fixed. The end of the strap A forms a socket, C, into which is closely fitted a pivot, D. Upon the upper side of the socket C I form a slot, d, and in the pivot D a corresponding slot, a, (see figs. 3 and 5,) so that when the pivot D is in the position denoted in fig. 4 the slots in the pivot and socket correspond. The strap B is formed with two heads, E, about the size of the socket C, or larger than pivot D, and so as to enclose the socket C, as seen in fig. 2. Between the two heads extends a bar, f, (see fig. 6,) which said bar is formed to set through the slot d in the socket, and fit closely into the slot a in the pivot D, as seen in figs. 3 and 4.

To insert the part B into the socket so as to attach the pole or shaft to the axle, raise the part B to the position denoted in fig. 4, and insert the bar f through the slot d into the pivot; then turn the part B down, as seen in fig. 3, which is about the position for general use. To prevent the pivot D from being displaced in the absence of the pole or shaft connections, I form a groove, a, partially around the said pivot, as see figs. 3 and 5, and into the socket C I place a pin, i, which enters the said groove in the socket, and prevents its displacement, and also serves the important purpose of stopping the said pivot when at the proper position for the insertion or removal of the pole or shafts, as seen in fig. 4. To prevent "rattling," I insert in the slot a in the pivot, and beneath the bar f, a thin piece of India rubber, or other similar material, as seen in figs. 3 and 4.

I do not broadly claim a carriage shackle when constructed with a slot and pivot, so that the shafts may be attached or detached by raising to a given point, as such is not new, as may be seen in the patents to E. W. Seymour, February 25, 1862, and L. T. Hazen, September 16, 1862.

Having, therefore, thus fully described my invention, what I claim as new and useful, and desire to secure by Letters Patent, is—

1. The combination and arrangement of the bar f, extending between the heads E, with the socket C, and pivot D, each constructed with a slot their entire length, to receive the bar f, and so as to operate substantially in the manner herein set forth.

2. The arrangement of the groove a on the pivot D, and the pin i in combination with the socket C, substantially as and for the purpose specified.
